UNITED STATES PATENT OFFICE

149,868

DESIGN FOR A CLOCKCASE

Lewis H. Gustafson and Lewis J. Halberstadt,
Northampton, Mass., assignors to Pro-phy-lac-
tic Brush Company, Northampton, Mass., a
corporation of Delaware

Application August 15, 1947, Serial No. 140,904

Term of patent 3½ years

(Cl. D42—7)

To all whom it may concern:

Be it known that we, Lewis H. Gustafson and Lewis J. Halberstadt, citizens of the United States of America and residents of Northampton, in the county of Hampshire, Commonwealth of Massachusetts, have invented a new, original, and ornamental Design for Clockcase, of which the following is a specification, reference being had to the accompanying drawing, forming part thereof.

In the drawing:

Fig. 1 is a view in front elevation of a clockcase showing our new design.

Fig. 2 is a side elevation thereof.

We claim:

The ornamental design for a clockcase, substantially as shown.

LEWIS H. GUSTAFSON.
LEWIS J. HALBERSTADT.
